UNITED STATES PATENT OFFICE.

EUCLID P. WORDEN, OF MILWAUKEE, WISCONSIN, ASSIGNOR TO FRED M. PRESCOTT STEAM PUMP COMPANY, OF WEST ALLIS, WISCONSIN, A CORPORATION OF WISCONSIN.

PUMP.

No. 837,995.

Specification of Letters Patent.

Patented Dec. 11, 1906.

Application filed July 14, 1904. Serial No. 216,458.

To all whom it may concern:

Be it known that I, EUCLID P. WORDEN, a citizen of the United States, residing at Milwaukee, in the county of Milwaukee and State of Wisconsin, have invented certain new and useful Improvements in Pumps, of which the following is a specification, reference being had to the accompanying drawings, forming a part thereof.

- 10 This invention relates particularly to pumps in which the suction and discharge valves are carried by decks or plates cast integral with and on opposite sides of the cylinders or pulsation-chambers and the suction-valve area is greater than the discharge-valve area. Its main object is to facilitate boring the valve-openings in said plates without enlarging the discharge-chamber or making unnecessary joints in the castings.
- 15 It consists in certain novel features of construction and in the peculiar arrangement and combinations of parts, as herein-after particularly described.

In the accompanying drawings like letters 25 designate the same parts in both figures.

Figure 1 is a longitudinal section on the line 1 1, Fig. 2, through one side of a duplex pump embodying my invention; and Fig. 2 is an end elevation and vertical cross-section, 30 on the line 2 2, Fig. 1, of the same.

For the purpose of illustration the invention is shown as embodied in a duplex pump in which the two plunger or pulsation chambers are arranged horizontally side by side 35 and the discharge and suction chambers above and below them; but it is applicable to single pumps and pumps of other kinds.

Referring to the drawings, *a* *a* designate the pulsation or plunger chambers, which are 40 each divided by partitions *b* into two parts.

c designates one of the plungers fitted to work in a sleeve or bushing in the partition *b*.

d is the suction-chamber, which is cast integral with the plunger or pulsation chambers *a*, and *e* is the discharge-chamber, which is separately cast and detachably secured to said chambers by a flange and bolts or other means.

The suction-main is connected at *f* with 50 the suction-chamber and the discharge-main at *g* with the discharge-chamber.

The suction and discharge valve decks or plates *h* and *i* are cast integral with the

plunger-chambers below and above the same. A part of the suction-valve plate *h* is 55 formed in a plane parallel with the plane of the discharge-valve plate *i* and has a number of valve-openings *j* directly in line with and opposite corresponding valve-openings *k* therein. To provide greater suction-valve 60 area than discharge-valve area, as is frequently required in this kind of pumps, additional valve-openings *j'* are made in the plate *h*, and in order that these additional openings may be readily bored and threaded they are 65 formed in a plane at an angle to the other openings, but perpendicular to lines passing obliquely through the nearest or other convenient openings *k* in the upper plate, so that 70 boring and screw-cutting tools may be inserted obliquely through the openings in the upper plate, as indicated by dotted lines on Fig. 2, and the openings in the inclined or oblique part of the lower valve-plate may be bored and threaded from above, the discharge-chamber casting being removed when 75 these operations are performed.

The valve-openings being preferably bored and threaded with more or less taper to insure a tight fit therein of the valve seats and 80 guides, the boring and threading operations can be performed much more conveniently and satisfactorily from the upper or larger ends of the openings, and in this way the suction-chamber may be made integral with the 85 suction-valve plate and pulsation-chambers.

By making the extra valve-openings in the plate *h* in a plane perpendicular to lines passing obliquely through openings in the upper plate *i* the openings *j'* can be bored and 90 threaded as readily and accurately as the openings *j*, which are directly opposite and in line with the openings *k*, and the discharge-valve plate *i* can be cast integral with the pulsation-chambers without unnecessarily 95 increasing the size of the discharge-chamber *e*.

In the pump as herein shown there are three longitudinal rows of suction and discharge valve openings *j* and *k* arranged directly opposite and in line with each other in 100 parallel planes on each side of the pump, and there is an extra row of suction-valve openings *j'* formed in a plane inclined or oblique to the plane of the other openings and perpendicular to lines passing centrally and obliquely through the outer row of openings *k*.

in the upper plate; but the number and arrangement of the valve-openings may be varied, as well as other details of construction, without departing from the invention.

5 After the openings have been bored and threaded, as above explained, valve seats and guides *l* are screwed into them, and they are provided with valves *m* of the usual or any suitable kind, as shown at the right in 10 Fig. 1.

I claim—

15 1. A pump having valve-plates integral with and on opposite sides of a pulsation-chamber, one of said plates having a greater number of valve-openings than the other and being formed in two or more planes which are at an angle to each other and one or more of which are perpendicular to lines 20 passing obliquely through openings in the other plate, substantially as described.

25 2. A pump having suction and discharge valve plates integral with and on opposite sides of a pulsation-chamber, the suction-valve plate having a greater number of valve-openings than the discharge-valve plate and being formed in planes which are at an angle to each other and one or more of which are perpendicular to straight lines passing obliquely through openings in the discharge- 30 valve plate, substantially as described.

3. A pump having suction and discharge

valve plates integral with and on opposite sides of a pulsation-chamber, a suction-chamber also integral with said pulsation-chamber and valve-plates, and a discharge-chamber 35 detachably secured to said pulsation-chamber, the suction-valve plate having a greater number of valve-openings than the discharge-valve plate and being formed in planes which are at an angle to each other 40 and one or more of which are perpendicular to straight lines passing obliquely through openings in the discharge-valve plate, substantially as described.

4. A pump having suction and discharge 45 valve plates on opposite sides of a pulsation-chamber, the suction-valve plate having a greater number of valve-openings than the discharge-valve plate and having some of its openings in a plane parallel with the plane of 50 the discharge-valve plate and directly opposite and in line with openings therein and other openings in a plane oblique to the plane of the discharge-valve plate and perpendicular to straight lines passing obliquely through 55 openings therein, substantially as described.

In witness whereof I hereto affix my signature in presence of two witnesses.

EUCLID P. WORDEN.
